UNITED STATES PATENT OFFICE

136,301

DESIGN FOR A TEETHING DEVICE

Roland S. Claflin, Park Ridge, Ill.

Application June 7, 1943, Serial No. 110,382

Term of patent 14 years

To all whom it may concern:

Be it known that I, Roland S. Claflin, a citizen of the United States, residing at Park Ridge, in the county of Cook and State of Illinois, have invented a new, original, and ornamental Design for a Teething Device, of which the following is a specification, reference being had to the accompanying drawing, forming part thereof, in which—

Fig. 1 is a plan view of a teething device showing my new design;

Fig. 2 is a view in side elevation of the teething device; and

Fig. 3 is a view in side elevation of the teething device, this view being taken at right angles to Fig. 2.

I claim:

The ornamental design for a teething device, substantially as shown.

ROLAND S. CLAFLIN.
